United States Patent Office.

JAMES A. PRINTZ, OF READING, PENNSYLVANIA.

Letters Patent No. 106,279, dated August 9, 1870.

IMPROVEMENT IN SASH-HOLDERS.

The Schedule referred to in these Letters Patent and making part of the same.

To all whom it may concern:

Be it known that I, JAMES A. PRINTZ, of the city of Reading, county of Berks, and State of Pennsylvania, have invented an Improved Sash-Lock and Supporter; and I do hereby declare the following to be an exact description thereof, reference being had to the accompanying drawing and to the letters of reference marked thereon making a part of this specification, in which—

Figure 1 represents a side elevation of the sash-lock and supporter;

Figure 2, an opposite side view of the same; and

Figure 3, an end view of the same.

The nature of my invention consists in the combination of the spring roller-box, operating on a vertical plate, the box having two circular inclines for the journal of the roller to shift or raise and lower in, and of the hinged-plate F, spiral spring, and supporter, with operating button, all as arranged and combined.

The object is to lock and support the sash at any required height, and in raising and lowering the sash it has a free and yielding operation.

To enable others skilled in the art to make and use my invention, I will proceed to describe its construction and operation.

A represents the vertical metallic plate, that is mortised and fastened by screws to the side of the sash, the devices for supporting the sash being permanently attached to the plate on its inside, and operating in the mortise of the sash.

B is the box, in which an India-rubber roller, E, op-

erates. The journals D D of the roller shift up and down in a double circular slot, C, in the sides of the box, as the sash is raised or lowered, so as to ease and free the roller as it presses against the side of the window-frame.

The box B is adjustable by means of the gum spring L, secured by a bolt, M, to the inside of the box, and the box works on a hinged plate, F, at the hinge N, the hinge being secured by its shaft to the circular side plates or stationary box P P. The other end of the hinge is a plate, R, that is regulated by the spiral spring G, and the projecting pin or supporter H is permanently attached to the plate R.

The bottom or knob J is also attached to plate R, so that the plate R, with the supporter H, can be moved back, and the supporter disengaged from the window-frame, into which it locks, by springing into apertures made on the inside of the window-frame, the sash resting upon the supporter H.

What I claim as my invention, and desire to secure by Letters Patent, is—

The combination of the spring roller-box B, having a double circular slot, C, for the journal D of the roller E to shift in, the hinged plate F, spiral spring G, and supporter H, with operating button J, when arranged and combined upon the same plate, as herein described, and for the purposes set forth.

JAMES A. PRINTZ.
